UNITED STATES PATENT OFFICE

HENRY EWALD OEHILKE, OF MANISTEE, MICHIGAN

AEROPLANE CONTROL STICK

Application filed October 10, 1928. Serial No. 311,464.

This invention relates to aeroplane sticks and more particularly to an aeroplane stick especially adapted for dual control systems wherein the control mechanism is operable by either the student's control stick or by the instructor's control stick.

One object of the invention is to provide a control stick of simple construction that may be easily and effectively disconnected from the aeroplane control system.

Another object is to provide a pair of control sticks constructed to permit the student's and the instructor's control stick to be easily interchanged with respect to the control mechanism.

Another object is the provision of a student's control stick comprising a pair of separable parts normally urged apart but held together by latch mechanism releasable from the instructor's station.

Other objects will appear as the description proceeds.

In the drawings:—

Fig. 1 is an elevational view illustrating my invention as applied to an aeroplane control system;

Fig. 2 is a sectional view showing details of construction of one of the control sticks;

Fig. 3 is a section taken on the line 3—3 of Fig. 2.

Referring to Fig. 1, the numerals 1 and 2 designate as a whole, a pair of control sticks positioned for operation from the stations 10 and 11, one of which may be occupied by the student and the other by the instructor. It sometimes happens that the student becomes frightened and holds on to his control stick with such force that the instructor is unable to manipulate his control stick and to avoid this difficulty, I have provided means for instantly separating the student's control from the controlling mechanism.

The control mechanism operated by the two control sticks may be of any conventional design and as illustrated, comprises a pair of hollow tubular members 3 and 4 to which a connecting bar 7 is pivoted at 17 and 20. A bar 5 journaled in brackets 6 is also pivoted to the members 3 and 4 at 18 and 19.

Certain of the control wires, the aileron wire

and the elevator wires, are designated by the numerals 8 and 9, respectively.

A socket member 13 is adapted for connection with the aeroplane control system preferably through an integral hollow tubular part 14 fitting into either of the tubular members 3 or 4 and secured thereto by means of the pin 17 as shown in Fig. 2. The numeral 22 designates the control handle or the handle portion of the control stick and has secured thereto the conical socket member 12 to fit into the conical socket member 13.

A coil spring 15 has a ring portion 16 anchored to the pin 17 within the tubular part 14 of the socket member 13 and in its normal expanded position extends into the conical member 13.

In the assembly of the control stick, the socket member 12 is inserted into the socket member 13 against the pressure of the spring 15. In order to hold the socket members 12 and 13 rigidly together against the force of the spring 15, I provide a readily releasable latch mechanism operable from the instructor's station to instantly disconnect the student's control handle comprising the parts 12 and 22 from the member 13 attached to the control mechanism. A simple, convenient and inexpensive mechanism for this purpose may comprise a split pin inserted through aligned holes in the co-operating socket members 12 and 13 with a wire or cord connected to the ring part 21 of the split pin and directed into the instructor's station. A split pin is found to be more advantageous for this purpose than a solid pin because it takes up whatever play may be caused by the holes in the socket members, as the holes must, for convenient operation, be somewhat larger than the pin.

The handles 22 may, as shown in Fig. 2, be detachably connected with the socket member 12 by means of a set screw 25 so that different style handles may be used. However, the handle portion 22 may be rigidly secured to or integral with the socket member 12 and I desire it to be understood that the handle or handle portion of the control stick includes the parts 22 and 12 as a unit.

To more clearly comprehend the mode of

operation of my invention, it may be assumed that the student occupies the station 10 and that the instructor occupies the station 11. The control cord 23 connected to the instructor's control stick will then be placed in an out of the way position, as wrapped around the control stick 2. The control cord 23 attached to the release pin of the student's control stick 1 will extend back to the instructor's station 11, convenient to the instructor. In case the student gets confused or frightened at a critical time, the instructor simply gives the cord a quick jerk, withdrawing the split lock pin, and the socket member 12 with the student's handle, is forced out of its socket member 13 by the spring 15, instantly disconnecting the student's handle from the control mechanism and permitting operation thereof by the instructor's control stick. The control sticks 1 and 2 may be of identical construction and if the student occupies the station 11 instead of the station 10, the cord 23 for the control stick 1 will be placed in an out of the way position and the instructor will, in case of danger, jerk the string 23 leading back to the student's control stick 2.

If desired, only the control stick for the student's use may be constructed as shown in Fig. 2, in which case the student's and instructor's control sticks may be interchanged when the position of the student and instructor is reversed. The instructor's control stick may then simply have a socket portion adapted to be locked to either of the socket members 13 without the interposition of the spring 15.

It is also apparent that the female socket member and spring may be carried by the handle portion and the male socket portion connected with the control mechanism.

Obviously those skilled in the art may make various changes in the construction and arrangement of parts without departing from the spirit and scope of the invention as defined by the claims hereto appended, and I therefore do not wish to be restricted to the precise construction herein disclosed.

I claim:

1. An aeroplane control stick comprising in combination, a handle portion, a member adapted for connection with an aeroplane control system, means tending to force said handle portion and member apart and out of operative relation with each other, latch mechanism detachably connecting said handle portion and member together against the force of said means, and means for releasing said latch to separate said handle portion from said member.

2. An aeroplane control stick comprising in combination, a handle portion, a member adapted for connection with an aeroplane control system, a spring tending to force said members apart and out of operative relation with each other, and releasable latch mecha-

nism detachably connecting said handle portion and member together against the force of said spring.

3. An aeroplane control stick comprising in combination, a handle portion, a member adapted for connection with an aeroplane control system having a socket receiving said handle portion, a spring tending to force said handle portion and member apart and out of operative relation with each other, and releasable latch mechanism detachably connecting said handle portion and member together against the force of said spring.

4. An aeroplane control stick comprising in combination, a handle portion, a member having a socket for receiving said handle portion and a tubular part adapted to be received within a tubular part of an aeroplane control system, a spring within said tubular part tending to separate said handle portion and member, and releasable latch mechanism connecting said handle portion and member together against the force of said spring.

5. An aeroplane control stick comprising in combination, a handle portion, a member adapted for connection with an aeroplane control system having a socket for receiving said handle portion, a spring tending to force said handle portion and member apart, and a releasable pin extending through said handle portion and member to hold said handle portion and member together against the action of said spring.

6. An aeroplane control stick comprising a pair of separable members, one of said members constituting a handle portion and the other of said members being adapted for attachment to an aeroplane control system, a socket on one of said members receiving the other of said members, resilient means forcing said members apart and out of operative relation with each other, and a releasable latch mechanism holding said members together against the force of said resilient means.

7. An aeroplane control stick comprising in combination a socket having a tubular portion adapted for connection with an aeroplane control system, a handle portion fitting into said socket, a spring within said tubular portion anchored thereto and bearing against said handle portion, and a releasable latch means holding said handle portion into said socket against the force of said spring.

8. In an aeroplane control system, a student's control handle, an instructor's station and control handle, control mechanism operable by each of said handles, resilient means tending to force said student's handle out of operative engagement with said control mechanism, latch mechanism detachably connecting said student's handle with said control mechanism against the force of said resilient means, and releasing means for said

latch mechanism operable from said instructor's station.

9. In an aeroplane control system, a student's control handle, an instructor's station and control handle, control mechanism operable by each of said handles, co-operating members connecting said student's handle to said control mechanism, an expansible means forcing said members apart, releasable latch mechanism holding said members together against the force of said expansible means, and means connected with said latch mechanism operable from said instructor's station to release said latch mechanism.

10. In an aeroplane control system, a student's control handle, an instructor's station and control handle, control mechanism operable by each of said handles, co-operating members connecting said student's handle to said control mechanism, a spring forcing said members apart, a pin holding said members together against the force of said spring, and means connected with said pin operable from the operator's station for withdrawing said pin.

11. In an aeroplane control system, a student's control handle, an instructor's station and control handle, control mechanism operable by each of said handles, attaching members carried by said mechanism for said handles, co-operating members on each of said handles adapted to be connected with either of said attaching members, means tending to force one of said attaching members into inoperative relation with its co-operating member, latch mechanism holding said last named attaching member and co-operating member together against the force of said means, and releasing means for said latch mechanism operable from said instructor's station.

12. In an aeroplane control system, a student's control handle, an instructor's station and control handle, control mechanism operable by each of said handles, co-operating socket members connecting said student's handle to said control mechanism, a spring forcing said socket members apart, a pin holding said socket members together against the force of said spring, and means comprising a flexible element connected with said pin extending into said instructor's station for withdrawing said pin.

13. An aeroplane control stick comprising in combination, a conical socket member having a tubular portion adapted for attachment to an aeroplane control system, a coil spring anchored within said tubular portion and expansible into said socket member, a handle portion having a conical part fitting into said socket member, and a releasable pin extending through said socket member and handle portion for holding said socket and handle portion together against the force of said spring.

14. In an aircraft, a system for controlling movement thereof and including first and second control stations, a controller element operatively connected to the system and located in the first station, a socket operatively connected to the system and located in the second station, spring means disposed in the socket, a second controller element located in the socket, means for retaining the second controller element in such position within the socket as to retain the spring means under compression, and means operative from the first control station for releasing said retaining means, whereby the second controller element is forcibly ejected from the system.

15. An aeroplane control stick comprising in combination, a socket member having a tubular portion adapted for attachment to an aeroplane control system, a coil spring anchored within said tubular portion and expansible into said socket member, a handle portion having a part fitting into said socket member, and a releasable means extending through said socket member and into said handle portion for holding said socket and handle portion together against the force of said spring.

In testimony whereof I have signed my name to this specification on this 4th day of October, A. D. 1928.

HENRY EWALD OEHLKE.
